[57] CLAIM

The ornamental design for a telephone, as shown and described.

DESCRIPTION

FIG. 1 is a perspective view of the telephone showing our new design including a telephone base and a telephone handset;

FIG. 2 is a rear elevational view of the telephone base;

FIG. 3 is a top plan view thereof;

FIG. 4 is a front elevational view thereof;

FIG. 5 is a left side elevational view thereof;

FIG. 6 is a bottom plan view thereof;

FIG. 7 is a right side elevational thereof;

FIG. 8 is a top plan view of the telephone handset;

FIG. 9 is a left side elevational view thereof;

FIG. 10 is a bottom plan view thereof;

FIG. 11 is a rear elevational view thereof; and,

FIG. 12 is a front elevational view thereof.

The telephone base and handset have been shown separately in FIGS. 2-12 for convenience of illustration.

The broken line disclosure in FIG. 1 is for illustrative purposes only and form no part of the claimed design. The notch on the bottom edge of the protruding speaker end of the telephone in FIG. 9 has not been shown in FIG. 1 for convenience of illustration.
